By his Attorney
J.B. McGivern

UNITED STATES PATENT OFFICE.

GEORGE B. THOMPSON, OF RICHMOND HILL, NEW YORK.

FIGHTING BAG.

Application filed February 9, 1927. Serial No. 166,871.

My invention relates primarily to punching bags, and of devices in connection therewith, of an anchor suspended between the support and the bag which permits the 5 same to be punched, no matter how vigorously, but without noise, while in addition thereto it provides exercise for one or more boxers at the same time.

The invention consists of a small anchor. 10 As shown, it is round and about the size of a baseball, being solid and provided with means for suspending the same between the support and the bag, whereby it will control the movements of the bag. 15 Another object of my invention is to suspend the punching bag and cause the same to be even more lively than at present so as to cause the boxer to think quick as well as to teach him to dodge and side-step. It 20 will also train his eye, cause him to judge distance as well as give him active foot work, all of which tends to build up the muscles.

My invention further consists in certain 25 new and novel means for anchoring a punching bag in mid air which will add materially to the enjoyment of the family, as all may exercise therewith without that noise that is usual by the striking of the 30 ball against the striking board or upper support.

Prior to my invention punching bag apparatus of the type commonly used have employed a striking board from the center 35 of which the bag was suspended, the boxer standing within striking distance and by hitting the bag a blow cause it to strike against the board, the striking causing not only a noise but also a vibration, especially 40 if it were set up in the apartment, which causes the same to be very objectionable, which my present invention, among other things, is designed to prevent. In other punching bags there is also great lack of 45 efficiency due to the fact that the bag is limited in its operation, preventing the boxer from securing the greatest amplitude of action that he would or should from such apparatus. This difficulty my invention aims to over- 50 come in the manner that will be more clearly understood from the following disclosure of a selected embodiment of my invention. These and other objects and features of the invention will be hereinafter described and 55 pointed out, particularly in the appended claims.

My invention as at present preferred will be more clearly understood by reference to the drawing which illustrates merely examples of means for putting my invention 60 into practice and wherein

Fig. 1 is a view of a punching bag suspended by a yielding elastic rope having two anchors thereon, and showing in dotted lines, some of the various positions the bag 65 and anchors assume;

Fig. 2 is a side view of one form of anchor, showing eye screws for securing the elastic rope to;

Fig. 3 is a vertical sectional view of a 70 modified anchor showing the same with a bore and a rope clamping means contained therein;

Fig. 4 is another modification; with the anchor in two halves and a clamping means 75 operable on the assembling of the halves;

Fig. 5 is a detail elevation of the lower part of Fig. 3 showing means for locking the elastic rope and holding the same secure; 80

Fig. 6 is another modification, and

Fig. 7 shows a performer exercising with a punching bag having a single anchor.

My invention may be set up for use in any hall, or even a room of any apartment, 85 and by the means shown and hereinafter described there will be no vibrations or noise. The anchors may be made in any number of styles for keeping the bag always within a reasonable distance of the boxer 90 at all times. The punching bag, it will be understood, is of the usual style that is inflated, and incased within a suitable leather covering that may be laced or otherwise secured. The upper end of the punching 95 bag I prefer to secure to the elastic supporting rope or cord. Again it will be understood that a ball or bag may be filled with some heavy substance so as to afford more resistance to the blows, at the same 100 time requiring more strength on the part of the boxer.

Referring to Figure 1, a punching bag 8 is suspended by an elastic rope 9 having, as shown, between the supporting means 105 and the bag, two anchors, 10 and 11, each anchor having screw eyes 12, 13. The lower one, 10, controls the movement of the bag 8, and the anchor 11 controls the movement of the anchor 10. By providing two anchors 110 the punching bag is caused to be very active, causing the boxer to be on the alert to catch

it on its advancing or retreating movement. The boxer gets the active exercise with a bag so suspended, as he will use every movement used in shadow boxing, yet have the added advantage of the ball swung at every angle, and getting in blows that otherwise he would not practice.

As shown in said figure the elastic cords 9 are applied to the eyes 12 and 13 on said anchors by snap hooks 14, so that the punching bag outfit may be set up and taken down without trouble. Instead of elastic cords or ropes, as above referred to, they may consist of suitable springs which would in every way provide the necessary elasticity to the bag. By providing a practice bag as shown, the boxer may get the best exercise by reason of the lively and rapid manner he will have to step around to place blows on the bag, be they straight jabs, upper cuts or others, at the same time as has been noted, by the means shown the noise is reduced to a minimum by reason of having no kind of supporting bracket or board to receive the concussions of the bag.

It may be advantageous and desirable that the elastic cord be in one piece, and to move the anchor or anchors, as may be desired, to the most desirable place thereon. As shown 30 in Fig. 3 the anchor is provided with a central bore 15, having a tapered portion 16 and an enlarged bore 17 at its lower end. A sleeve 18 is adapted to fit into the lower bore 17, while the sleeve at its upper end is 35 adapted to house a two part clamp 19, which when the sleeve is pushed upwardly causes the clamping member 19 to pinch the elastic cord and hold the same tightly. The anchor 10 has a locking slot 20, while the sleeve has 40 a pin 21, which fits within said slot and is caused to lock and hold the anchor in any desired position.

With the punching bag suspended as shown, the boxer may acquire any style of 45 blows, and he has to keep a keen eye on the bag to get the best results from his exercise, the yielding swinging bag is ever before him for a jab, upper cut or any of the other numerous blows that are practiced, and he has to step, dodge and duck as in a 50 fight to prevent the ball from hitting him, all of which brings into action muscles that otherwise would not receive such necessary tryouts.

Referring to Fig. 4 wherein is shown an anchor consisting of members 22 and 23, which are adapted to be secured together by means of a screw thread 24, the upper member 22 has a beveled or cone shaped bore 55 25, terminating in a straight bore 26, while the lower member 23 has a straight bore 27 through the same, while on its upper part is provided clamps 28, which are formed by turning a cone, then splitting the same with 60 saw cuts 90 degrees to each other; thus when

the elastic cord or rope is put through the openings in the two members, and then screwed securely together, the elastic rope will be pinched and the anchor held in position against all the blows that will be delivered to the bag.

It will be understood, as before noted, that these anchors may be of any desired shape, for instance, as shown in Fig. 6, an ordinary window weight 29 may be used. As shown, 75 this anchor is provided with a longitudinal bore 30, its lower part having an enlarged threaded opening 31, which terminates in bevel or cone opening 32. The clamp herein shown comprises a threaded nut 33, and having a cone head 34, which as described in connection with Fig. 4, said cone may be saw cut 90 degrees each way so as to afford a positive clamp for the elastic rope or cord 80 that may be used.

Fig. 7 shows the movements of the bag when given a hard blow. The anchor 10 in this case is for small confined quarters, or for use of amateurs for the exercise that may be secured from this apparatus.

In accordance with the provisions of the patent statutes, I have herein described the principal form of my invention which I now consider to represent the best embodiment thereof, but I desire to have it understood 95 that the various form of anchors are only illustrative and that the invention may be carried out in other ways than those shown or described, but all are intended to come within the scope of the claims. While the 100 design of the anchors are shown in various forms, they may be changed or altered to meet the particular requirement without interfering in any way with the general results for which the anchors were designed.

What I claim and desire to secure by Letters Patent is:

1. An exercising apparatus comprising a member adapted to be struck, means for suspending the member from an overhead support to permit free swinging movement of said member when it is struck, and weighted means carried by the suspending means and having a greater inertia than the member thereby to quicken the movement of said member under the influence of a blow.

2. An exercising apparatus comprising a member adapted to be struck, flexible means for suspending the member from an overhead support to permit free swinging movement of said member when it is struck, and weighted means carried by the suspending means and having a greater inertia than the member thereby to quicken the movement of said member under the influence of a blow.

3. An exercising apparatus comprising a bag adapted to be struck, inherently flexible and resilient means for suspending the bag from an overhead support to permit free

swinging movement of said member when it is struck, and weighted means carried by said suspending means between its ends and having a greater inertia than the member 5 thereby to quicken the movements of said member under the influence of a blow.

4. An exercising apparatus comprising a bag adapted to be struck, inherently flexible and resilient means for suspending the bag 10 from an overhead support to permit free swinging movement of said member when it is struck, said suspending means being attached to the bag at one of its ends and to the support at its other end, and weighted 15 means carried by said suspending means and located between its ends and having a greater inertia than the member thereby to quicken the movement of said member under the influence of a blow.

20 5. An exercising apparatus comprising a bag adapted to be struck, means for suspending the bag from an overhead support to

permit free swinging movement of said bag when it is struck, and plurality of weighted members carried by said suspending means 25 and having each a greater inertia than the bag thereby to quicken the movements of the bag under the influence of a blow.

6. An exercising apparatus comprising a bag adapted to be struck, means for suspending the bag from an overhead support to 30 permit free swinging movement of said bag when it is struck, said means being flexible, and plurality of weighted members carried in spaced relationship to each other on the 35 suspending means, and each having a greater inertia than the bag, and working against each other and the bag under the influence of a blow on the bag to quicken the movements of the bag. 40

In testimony whereof I affix my signature.

GEORGE B. THOMPSON.
